UNITED STATES PATENT OFFICE.

SIMEON C. LAWLIOR, OF CHICAGO, ILLINOIS.

MOP-WRINGER.

1,378,879.

Specification of Letters Patent. Patented May 24, 1921.

Application filed February 17, 1919. Serial No. 277,474.

To all whom it may concern:

Be it known that I, SIMEON C. LAWLIOR, a citizen of the United States, residing at Chicago, in the county of Cook and State of Illinois, have invented certain new and useful Improvements in Mop-Wringers; and I do hereby declare the following to be a full, clear, and exact description of the invention, such as will enable others skilled in the art to 10 which it appertains to make and use the same.

This invention relates to wringers, particularly for mops, for use with pails or buckets into which the exuded fluid may be 15 received.

An object is to embody in a device of this character a stand or support which may be readily moved from place to place over a floor, and which may be anchored or held 20 from movement automatically upon the operation of the device to wring a mop; and to provide the device with novel means for insuring the collection and diverting into the pail or bucket of the fluid exuded from the 25 mop and which may collect upon the roller supports and adjacent parts of the device.

With these and further objects in view as will in part hereinafter become apparent and in part be stated, the invention comprises 30 certain novel constructions, combinations and arrangements of parts as subsequently specified and claimed.

In the accompanying drawings,—

Figure 1 is a side elevation of a mop wringer shown in open position and readily movable over the floor.

Fig. 2 is a top plan view of the same.

Fig. 3 is a horizontal section taken through the lower portion of the wringer substantially in the plane indicated by the line 3—3 of Fig. 1.

Fig. 4 is a detail, enlarged, sectional view taken through one of the rollers and its adjustable support, substantially in the plane indicated by the line 4—4 of Fig. 3.

Fig. 5 is a fragmentary, enlarged section taken through the upper part of the frame at one side, substantially in the plane indicated by the line 5—5 in Fig. 2.

Fig. 6 is a fragmentary, enlarged plan view of one end of the movable mop roller, and

Fig. 7 is a transverse section taken through the same, substantially in the plane indicated by the line 7—7 in Fig. 6.

Referring to the drawings by numerals, 10 indicates a pail or receptacle supporting base which is preferably formed of a metallic strap set on edge and reinforced by cross straps 11 and 12 connecting opposite points 60 of strap 10 and forming the bottom or supporting portion of the base upon which the pail or other receptacle 13 is designed to be sustained. The base 10 is carried on casters 14 and 15 arranged in pairs near the opposite 65 ends of the base 10. The casters 14 are mounted in suitable brackets 16 of strap metal which are riveted or otherwise suitably secured to the opposite sides of the base 10 near one end thereof, which end may be 70 designated as the rear or inner end of the base.

The casters 15 are mounted in brackets 17 having upstanding stems 18 journaled in supporting brackets 19 of preferably U- 75 shape and which embrace the adjacent side portions of the base 10 and have their flanges projecting inwardly in superposed relation to form spaced supports for the stems 18. The stems 18 are slideable vertically through 80 the brackets 19 and are normally urged downward by springs 20 bearing at their upper ends beneath the top flanges of the brackets 19 and being supported at their lower ends upon washers or other suitable abutments 21 carried upon the stems 18 above the lower flanges of the brackets 19. The washers 21 are adapted to engage the lower flanges of the brackets 19 and limit the downward thrust of the stems 18 for maintaining the 85 casters 15 in position on the base 10 when the latter is raised from the floor. The casters 15 are mounted on the base 10 in spaced relation to the outer or front end thereof, and mounted upon said front end of the base 10 90 are one or more feet 22 formed preferably of strap metal riveted or otherwise suitably secured to the strap forming the base and depending therefrom. The lower end of the feet are turned inwardly to form flat engaging portions which are spaced slightly above the floor when the base 10 supports its normal load, and the springs 20 are proportionately tensioned to sustain the feet 22 in such elevated position at normal times. For as- 95

sisting in lowering the forward end of the base 10 and maintaining it from movement over the floor, foot pieces 23 may be secured intermediately to the opposite sides of the base 10, and may be of similar construction 100

105

110

to the feet 22 with the exception that the lower ends of the foot pieces 23 are turned outward to receive the foot thereon for enabling the user to throw his weight upon the 5 base 10 to lower it.

Upstanding from each side of the base 10 is a side frame, which, for facility of manufacture, may consist of a standard 24 and a standard 25 which are merely continuations of the connecting straps 11 and 12 and which are riveted to the strap forming the base 10. The upper ends of the standards 24 and 25 are preferably laterally curved or bent to approach each other at the upper 15 end of the side frame, and are connected thereat by a plate 26 which is riveted to both standards. A cross bar or plate 27 connects the two top plates 26 and has its opposite ends riveted or otherwise suitably 20 secured thereto. Each top plate 26 extends vertically above the respective standards 24 and 25 and is bent to a horizontal position across the upper edge thereof to form a ledge 28, and then again bent to an up- 25 standing position to form a supporting and guide flange 29. The flanges 29 are slotted, as at 30, and the plate at the lower edge of the slot is bent outwardly to form a broad trackway or support 31 for the re- 30 ception of the adjacent trunnion 32 of the movable wringer roller 33. The flange 31 thus formed provides a relatively broad trackway adapted to resist wear and provide a firm substantial supporting surface 35 for the roller 33. The ledge 28 of each top plate 26 is provided with a longitudinally extending slot 34 for receiving and guiding an actuating arm hereinafter mentioned.

A bail-like lever 35, forming a treadle, 40 has its ends pivoted as at 36 to the standard 25 and its intermediate or closed portion up- 45 standing over the forward end of the base 10 and provided with a suitably attached tread plate 37. Pivoted to the respective sides of the treadle 35, intermediate the 50 pivot point 36 and the tread plate 37, are the respective upstanding arms 38 which extend through and are guided by the respective slots 34, the slots being of a size 55 loosely accommodating the arms but of sufficiently snug fit to prevent any excessive lateral or edgewise play. Each arm 38 is bent edgewise substantially midway of its length for causing the upper end of each arm to 60 travel laterally a greater distance than it would otherwise travel for the purposes hereinafter mentioned. It is to be noted also that the connection at the lower end of each arm 38 is spaced from the respective 65 pivot 36 a distance sufficient for causing the lower end of each arm to always remain outside the vertical, transverse planes of the slots 34, so that each arm 38 extends on an incline longitudinally through the respec- 70 tive slot. A spring 39 is preferably ar-

ranged at each side of the frame with its upper end connected to the adjacent top plate 26 and its lower end connected to the treadle 35 for maintaining the treadle 35 in a normally raised position. A wringer 70 roller 40 extends across from one side frame to the other and is journaled in the forward portions of the flanges 29 of the top plates. A movable wringer roller 33 is journaled in the upper ends of the arms 38, one of the 75 journals of the roller 33 extending beyond the respective arm and being provided with an operating crank 41. The journals 32 of each movable roller preferably consist of a reduced shaft fixed to and outstanding from 80 the ends of the roller, and may be connected in suitable manner to the arms 38 for holding the journals 32 from longitudinal movement through the arms.

While the wringer rollers 40 and 33 may 85 be of any preferred type or construction, it is preferable to construct the fixed roller 40 with an uninterrupted smooth peripheral surface and to provide the movable wringer roller 33 with alternately arranged slots and 90 circular openings, as shown in detail in Figs. 6 and 7, to facilitate the extraction of moisture from the mop without injury to the same.

Each top plate 26 is provided in the ledge 95 thereof with a drain opening or perforation 42 and a surrounding bead or raised portion 43 forming a wall adapted to confine fluid dripping from the guide trap 31 and for directing the fluid to the drain opening 42. 100 The connecting bar or plate 27 is preferably of sheet metal and is stamped substantially U-shape. The closed portion of the U-shaped plate 27 is arranged between the forward ends of the top plates 26 and laps 105 beneath the ledges 28 beyond the drain openings 42. Depressions or channels 44 are formed across the inner edge portions of the connecting plate 27 in line with the drain openings 42 and lead or open in a 110 position over the pail or bucket 13 for returning the collected fluid thereto. The outer ends of the channels 44 are closed as shown in Fig. 5. To enable the easy carrying or transporting of the device from 115 place to place, a handle or bail 45 is pivoted at a suitable point upon the upstanding flanges 29 of the top plates, and is adapted to be swung forwardly into a position out of the way, as shown in Figs. 1 120 and 2, when it is desired to wring mops.

For the purpose of reinforcing the base frame 10 and maintaining the cross straps 11 and 12 rigid, a brace strap 46 may be employed and is secured across the under sides 125 of the cross straps 11 and 12 midway between the sides of the frame 10. The brace strap 46 has at its forward end an upturned lip 47 adapted to assist in centering the receptacle 13 upon the straps 11 and 12, and 130

has at its rear end a depending foot 48 terminating in normally spaced relation from the floor and being adapted to arrest the backward tilting of the frame 10 and 5 the parts carried thereby should pressure be exerted upon any parts of the device to effect such tilting. By the provision of this foot 48 a more stable device is provided than in prior structures as the slight tilting which 10 may be effected before the foot 48 strikes the ground is not sufficient to dislodge the receptacle 13 or spill the fluid contents thereof.

In use, the device may be lifted and 15 carried by the handle or bail 45 and may be pushed or pulled over the floor to the desired location for use. When it is desired to wring a mop the user may place one foot upon the adjacent foot piece 23 to depress 20 the forward end of the base 10 and bring the feet 22 and pieces 23 into contact with the floor, thus anchoring or maintaining the base 10 from movement. The mop is placed between the rollers 33 and 40, the treadle 25 35 is depressed by the other foot to bind the mop between the rollers, and the roller 33 is turned as by the crank handle 41.

The foot pieces 23 stand out from the base 10 in convenient position to receive the ball 30 of the foot in the natural position assumed when the user stands close to the device. As both the feet 22 and the foot pieces may, though not necessarily so, bear against the floor the base is securely maintained against 35 accidental movement under pressure upon the hand crank 41 or pressure upon other parts of the device.

Either foot when engaging the respective 40 foot piece is in natural position for supporting the operator when applying the other foot to the treadle 35, pressure on the treadle further insuring the stability of the base 10.

The fluid exuded from the mop is deflected by the upstanding flanges 29 from 45 the fixed roller 40 upon the connecting bar 27 and back into the receptacle 13. However, usually the fluid which drops from the ends of the movable roller 33 and from the trunnions 32 thereof frequently passes out 50 through the guide slots 30 and over the trackways 31, dropping upon the ledges 28 outside of the flanges 29 and falling outside of the receptacle upon the floor. With the present construction the fluid escaping 55 through the slots 30 and over the trackways 31 falls upon the ledges 28 but within the wall or ridge 43. The fluid is thus trapped against the outer sides of the flanges 29 and escapes through the drain openings 42 and 60 channels 44 back into the receptacle 13.

Immediately pressure is relieved from the base 10, the springs 20 raise the floor contacts out of engagement with the floor, and the device may then be easily shifted to any 65 new position desired. Preferably, the casters

15 are swiveled upon their stems 18 so that the base 10 may be easily turned and manipulated.

I claim:

1. In a wringer, a supporting base, side 70 frames rising from the base, top plates carried by the said frames and having horizontal ledges and upstanding flanges at the inner margins of the ledges, a fixed wringer roller journaled in the flanges, a wringer 75 roller movably sustained by the side frames and adapted to move between the flanges, traps arranged on said ledges exteriorly of the flanges for catching fluid dripping from the rollers, and conveying means carried by 80 the side plates for carrying off the trapped fluid from the ledges.

2. In a wringer, the combination, of a base adapted to support a receptacle, side 85 frames rising from the base, fixed and movable wringer rollers mounted on the side frames, each side frame having a horizontal ledge with a fluid trap on the upper surface thereof having a drain opening leading beneath the ledge, and a connecting bar extending between the ledges and secured thereto and provided with depressed channels beneath said traps leading into a position 90 over the receptacle.

3. In a wringer, the combination, of a 95 supporting frame adapted to carry a receptacle and provided with side portions between which the receptacle is adapted to rest, wringer rollers carried by the side portions and adapted to extend over the receptacle, fluid collecting means for the side portions at the opposite ends of the roller supports for collecting fluid dripping from the rollers and their supports, and connecting means for the upper ends of the side portions 100 for maintaining the same in spaced relation and provided with conducting means for carrying off the collected fluid and delivering it into the said receptacle.

4. In a wringer, a pair of supporting 110 plates having upstanding flanges with arcuate slots extending diagonally downward from the upper edges of the flanges, a fixed roller carried between the flanges in spaced relation to the lower ends of said slots, a 115 movable roller having trunnions adapted to move in said slots for carrying the roller toward and from the fixed roller, said flanges having portions at the lower marginal edges of said arcuate slots turned laterally and following the curvature of the slots to provide relatively broad trackways over which said trunnions are adapted to travel.

5. In a wringer, the combination of a pair 125 of side plates having horizontal ledges and upstanding flanges at the inner margins of the ledges, each plate having an arcuate rib pressed up and terminating at opposite ends against the outer side of the adjacent flange 130

to form a trap for fluid and having a perforation within said rib to form a drain opening, and a connecting plate arranged between said side plates and secured in overlapping relation beneath the ledges thereof and having depressed channels extending from the inner edges of the connecting plate to a position beneath the openings in the ledges for conducting fluid from said traps

10 intermediately of said side plates.

6. In a wringer, the combination of side plates, each having an offset portion and a flange upstanding from the offset portion adapted to be positioned above a receptacle,

wringing rollers adapted, while in engagement with the upstanding flanges, to cooperate for wringing an article above the receptacle, and fluid-collecting means for the offset portions for directing fluid dripping from portions of the rollers into the receptacle.

In testimony whereof I affix my signature in presence of two witnesses.
